UNITED STATES PATENT OFFICE.

VERNON M. DEAN, OF DETROIT, MICHIGAN, ASSIGNEE OF TWENTY-FOUR AND ONE-HALF ONE-HUNDREDTHS TO EMMET C. DUBBS, OF DETROIT, MICHIGAN, AND TWENTY-FOUR AND ONE-HALF ONE-HUNDREDTHS TO WILLIAM B. JAMES, OF PORT HURON, MICHIGAN; THE DETROIT TRUST COMPANY EXECUTOR OF SAID WILLIAM B. JAMES, DECEASED.

INTERNAL-COMBUSTION ENGINE.

Application filed September 16, 1925. Serial No. 56,627.

The present invention relates to internal combustion engines and particularly to multi-cylinder engines.

In the conventional engine of the so-called four stroke cycle type, application of power to the crankshaft from each cylinder occurs during somewhat less than half of one revolution during two complete revolutions of the crankshaft.

Among the objects of the present invention is to substantially double the time power is applied by each cylinder to the crankshaft so that for each two revolutions of the shaft power is applied during substantially one whole revolution.

Another object is to increase such application of power while maintaining the advantages of the four stroke cycle type of engine.

Still another object is to substantially double the horse power of such engines without materially increasing the bulk thereof and to obtain the advantages of a multi-cylinder engine without materially increasing the length or resorting to a V-type arrangement of the cylinders.

Yet another object is a multi-cylinder engine in which the pistons are always in alignment with the cylinders and hence wear is evenly distributed about the cylinder and piston with consequent reduction.

Other objects include the reduction of noise in such engines, the improvement in lubrication, and substantial elimination of the necessity for frequent adjustments of one sort and another.

With these and other objects in view as will readily occur to those skilled in the art, the invention consists broadly in a double acting internal combustion engine having valve mechanism occupying a minimum of space and requiring only an initial adjustment, and also having means for delivering positively a plentiful supply of oil to all of the bearing parts.

Reference should be made to the accompanying drawings, in which:

Fig. 1 is a vertical section through one of the cylinders and valve mechanism therefor.

Fig. 2 is an end view of the engine with 50 parts removed.

Fig. 3 is a side elevation with part in section showing the valve mechanism and the manifolding.

Figs. 4 to 8 are enlarged details of parts 55 of the engine structure.

Fig. 9 is a view of one half of the crank case from the inside.

Fig. 10 is a diagrammatic end view of the type of crankshaft used in the engine. 60

In the drawings, the crank case of the engine is indicated at 15 with an oil pan at 16 and flywheel housing at 17. These parts will be supported in a suitable frame in more or less conventional manner. The 65 crank case 15 will, however, be provided with an upwardly extending portion 18 of less width than that portion having the shaft itself. This upper portion is designed to contain guides for cross heads 19, 70 to be described more in detail later.

Cross heads 19 will have pivotally connected thereto the connecting rods 20, whose lower ends in turn connect with the cranks 21 of crankshaft 22. It is proposed to insert between the cranks 21 and connecting rods 20 and also at the main bearings of shaft 22, suitable anti-friction bearings such as the ball bearings 23. 75

To the upper end of cross head 19 is secured a piston rod 25. This piston rod 25 extends up through a suitable packing, indicated as a whole by numeral 26, and carries at its upper end a piston 27 adapted to be reciprocated in cylinder 30. The packing 26 is secured in an intermediate lower cylinder head member 31 mounted on the upper part 18 of the crank case 15, while the cylinder 30 is mounted on the upper side of member 31, there being an upper head 90 member 32 surmounting the cylinder.

Piston 27 will be closed at both ends as indicated and secured to piston rod 25 as by clamping it on a taper 33 on said rod by means of a nut 34, and will be provided with 95 a set of packing rings 35 at each end and with an oil groove 36 about its middle between the rings.

As thus constructed, each cylinder will have two combustion spaces, one between piston 27 and head 32 and the other between piston 27 and the packing member 26 and 5 each of these spaces will be provided with a suitable ignition device such as a spark plug inserted in opening 37. Further, the cylinder 30 and each of the members 26 and 32 will be water-jacketed as indicated at 38. 10 In order that piston rod 25 may travel only axially, it is necessary that the side thrust, due to the operation of the connecting rods 20 in conjunction with the crank-shaft 22, be taken off this piston rod 25 and 15 this is done by the use of the cross head 19 and its guides. The latter are bearing plates 40 of suitable material set into the part 18 of the crank case and curved laterally and secured in any suitable manner. The cross 20 head 19 is shown in detail in Figs. 5 and 6 and consists of a body portion 41 provided with a boss 42 into which the lower end of piston rod 25 extends and is secured. Portion 41 is also provided with diametrically 25 opposite extensions 43 to which are secured the bearing shoes 44 adapted to slide in guides 40. Further, the body 41 is also provided with bosses 45 in which are secured the ends of connecting rod pins (not shown). 30 The shoes 44 are preferably secured to extensions 43 by tapering the edges of the latter and undercutting to form the male portion of the slide while the shoes are correspondingly provided with a female slide. 35 Shoes 44 are then fixed firmly on the slide by studs 46^a and nuts 46.

In order to permit a gas-pressure-tight lower head for the cylinder and yet permit sliding of piston rod 25 therethrough, a 40 packing gland such as is shown enlarged in Fig. 7 is used. In this figure, piston rod 25 is shown as passing through head 26 and the elements of the gland contained in a water-jacketed inner cylinder or case 50 forming 45 an integral part of the head casting. The lower end of cylinder 50 will project from head 26 and be threaded to receive a gland nut 51 which through a spring 52 maintains a pressure on the packing proper. The latter in the form shown consists of three rings 53 of a suitable anti-friction bearing metal each having one flat end surface and one internal cone shaped surface, together with a similar ring 54 having an external cone 55 surface, and another ring 55 having two external cone surfaces arranged as shown. All of these rings will be divided radially into several pieces and ring 55 will be slightly smaller in outside diameter than the others. 60 The end pressure of spring 52 causes the several rings to form a gas tight joint. In addition to the packing rings mentioned there is also another ring 56 which fits closely around the shaft and lies above the

others. This ring will not be divided and 65 will be stepped as shown. If desired, felt or other non-metallic ring 57 may also be used at the lower end of the packing to prevent a too free passage of oil from the packing back into the crankcase. 70

The valve mechanism for the engine is illustrated in Figs. 1 to 4 and 8. Driven from the end of the crankshaft by means of a suitable bevel gear 60 is a substantially vertical shaft 61 which through other bevel 75 gearing 62 drives a cam shaft 63, located about midway of the cylinders 30, carrying cams adapted to actuate the slide valves 64 through the tappets 65.

The valves of a vertical pair will be displaced laterally and actuated by double cams 63^a on shaft 63, one valve controlling a port in one end of a cylinder and the other a port in the other end. In the present arrangement, as indicated by the manifolding, each 85 pair of valves will consist of two intake valves or two exhaust valves, as the case may be.

The valves themselves are illustrated as 90 pistons adapted to be reciprocated in water-jacketed cylinders 66 having ports 67, diametrically located but vertically displaced as shown, adapted to register with a through 95 passage 68 in each of the valves 64. The construction and operation of these valves is more particularly described and claimed in application Serial Number 45,476, filed July 23, 1925, by the present applicant. The valves and their cylinders will be constructed as in that application except that the inverted cylinder will be provided with an oil drain 69 leading therefrom into the space 70 alongside of the crank case extension 18 which space communicates with the interior thereof. 100

As indicated, the cylinders 66 will be formed in integral lateral extensions on the cylinder heads 31 and 32, and the cam shaft 63 and tappets 65 mounted in the space between these extensions, the shaft being carried in ball bearings 75 mounted opposite the spaces between cylinders 30 and at the ends thereof, and the tappets carried in guide blocks 76 secured to the exterior walls of cylinders 30 between the cam shaft and the 110 valve cylinders. Each guide block 76 will consist of a casting having two parallel barrels 77 in which are bushings 78 providing the bearing surface for the tappets 65. The latter are cylindrical and have at one end of each a roller cam follower 79. Further, each tappet is provided with a lateral tongue or projection 80 adapted to slide in a slot 81 in bushing 78 so that the tappet and therefore the valve cannot rotate, these being fixed 120 together. Each block 76 is secured against a flat portion 82 of the outside wall of water jacket 38 of the cylinders by means of screws 125

83 in the holes 84 and 84^a, the latter being located so that a single screw aids in securing two blocks 76.

The chamber containing the cam shaft and 5 tappets will be covered in an oil tight manner by a plate 85, and the manifolds, exhaust and intake, will overlie the cover as indicated in Fig. 3. The exhaust manifold will 10 preferably consist of two parts 150 and 151 connected to the valve ports and may be joined to a common muffler pipe, if desired. The intake manifold 152 will lead from a common central inlet 153 to the several intake ports, a carburetor being connected in 15 the usual manner to part 153.

The lubrication of the engine is by means of a pressure system forcing oil under pressure to practically all of the bearing surfaces. In Fig. 2, there is shown a vertical 20 shaft 90, worn driven from the crank shaft. This shaft 90 carries at its bottom end a pump 91 and at its upper end is directly connected to the distributor (not shown) for the ignition system, and is mounted in a 25 vertically extending tube 92 formed as a part of the crank case, which tube is constricted at an intermediate point 93 to provide a bearing for the shaft 90. The shaft is also provided with suitable bearings 94 at 30 its lower end.

The pump 91 draws oil from the lower part of the crank case and forces it through pipe 95 to a longitudinal pipe or passage 96 formed in the crank case from which it is 35 distributed to the several bearings. From passage 96 the oil travels through passages 97 to the cross heads 19 and packing boxes 26 as shown best in Fig. 1. And, from the cross heads, the oil is led to the piston 27 40 and to each connecting rod bearing. This latter is accomplished by leading the oil from passage 97 to a groove 98 in one of the cross head bearing shoes which groove is long enough to be always open to the short passage connecting to passage 97. From groove 98, the oil travels to the other bearing shoe and up through piston rod 25, which is hollow, to the piston. The oil also passes into 45 passage 99 in the connecting rod 20 and so to the crank bearing therefor. The main bearings for the crank shaft 22 will be lubricated by passages 100 leading from tube 96 directly thereto. These passages 100 will be drilled 50 in the bearing supporting webs.

55 In order to lubricate the valve mechanism, a vertical pipe 105 is led from tube 96 to a point adjacent the chamber containing the cam shaft and into said chamber, being provided with an atomizing nozzle 106 as indicated in Fig. 1. The oil mist produced thereby fills the valve chamber and lubricates all of the working parts therein. Some of the mist finds its way up through the upper valve piston 64 and lubricated the latter, while some passes out into the casing

for gearing 62 and lubricates this. Some of the mist will collect in the bottom of the chamber and pass through the lower valves 64 into the spring containing chambers beneath, from which it drains through the 70 small drain 107 into the crank case. The mist which passes into the housing for gearing 62 collects above an oil retaining ring 108 carried by shaft 61 and drains into tube 92 above bearing 93 through passage 109. 75

An alternative method of supplying oil to the cam shaft chamber will be to lead it from pipe 105 into the chambers above the upper valve pistons through passages 106^a whence it passes through longitudinal 80 passages in these pistons to the chamber below, thus oiling all of the valve parts.

Fresh oil is supplied through filler pipe 115 leading into a cored-out chamber 116 from which it escapes through the openings 117 and 118 in the walls of tube 92, into the crank case. 85

Fig. 9 is a view, from the inside, of half of the crank case and shows the location of certain parts not clearly brought out in the other views. In this figure, the flywheel housing and therefore the rear of the engine is indicated at 120. The crank case proper is indicated at 15 and upper extension 18 is shown to be grid-like with openings 95 between the upright ribs or bars 121 and 122. Ribs 121 are really extensions of webs 123 extending across the case and furnishing support for the main bearings which will be supported in the bearing caps 124. 100 (Only one-half of each bearing support is shown except of the center one. In this case the under part is shown for clarity.) Ribs 122 are supported by webs 123 at the bottom and carry the cross head guide 105 plates 40.

In the complete engine, the space on either side of the extension 18 will be covered by the plates 18^a which extend from the upper part of the extension down to the crank case 110 15 and cover the openings between ribs 121 and 122, a gasket being used, if necessary, to make this cover oil-tight.

At 130 is shown one-half of the support for the lower bearing for shaft 61, and it 115 should be remarked that the tube 92 and pump shaft 90 are located across from shaft 61 in the front of case 15.

In Fig. 10 there is indicated the type of crankshaft that is used in the engine. This 120 is a 90 degree four-throw shaft with the four throws arranged spirally, that is, when the first throw is vertical, the second will be 90 degrees ahead; the third, also vertical but opposite; and the fourth 90 degrees behind the first. In other words, the four throws 201, 202, 203 and 204 will be at the four quadrants of the circle and in order 201 to 204. 125

Having now described the invention and 130

the preferred form of embodiment thereof, it is to be understood that the invention is not to be limited to the precise details herein described and illustrated but only by the scope of the claims which follow.

Claims—

1. A double acting internal combustion engine cylinder having at each end thereof a lateral extension with a valve cylinder therein, cooling means for said cylinder and said extensions, valves in said valve cylinders, a cam shaft located in the space between said lateral extensions and adapted to actuate said valves, and means to enclose said space to form an oil-tight chamber for said shaft and valve parts, and means to supply lubricant in the form of an oil mist to said chamber.
- 10 2. A double acting internal combustion en-

gine cylinder having at each end thereof a lateral extension with a valve cylinder therein, valves in said valve cylinders, a cam shaft located in the space between said lateral extensions and adapted to actuate said valves, means to enclose said space to form an oil-tight chamber for said shaft and valve parts, and means to supply lubricant in the form of an oil mist to said chamber.

15 3. In an internal combustion engine, a plurality of vertically arranged double acting cylinders, ports in each end of each cylinder, the ports opening to the same side of the cylinders, vertically arranged piston valves for said ports, and a single cam shaft arranged between the upper and lower valves for actuating the said valves.

VERNON M. DEAN.
